BEER DISPENSING APPARATUS

Hans Söllinger, St. Oswald, near Freistadt, Austria

Application September 4, 1936, Serial No. 99,427
In Austria March 18, 1936

2 Claims. (Cl. 225—1)

This invention relates to a beer dispensing apparatus by means of which beer can be dispensed without pressure from barrels situated at a lower level than the faucet.

5 The apparatus is also suitable for dispensing wine and cider and has, in known manner, a packing flange against which the vessel to be filled is pressed and hermetically closed by the suction action of the air pump. According to 10 the invention the dispensing faucet of the apparatus is connected by a gearing with the air pump by which, when the apparatus is in use, the air is drawn out of the beer glass pressed against the packing surface and then, when the dispensing faucet is subsequently opened and during 15 the filling of the glass, the excess carbon dioxide flowing into the glass passes into the pump whereupon, during the return movement of the gearing, the dispensing faucet is closed, and 20 the air and excess carbon dioxide in the pump is returned by the pump to the barrel through a filter.

An embodiment of the invention is illustrated by way of example in the accompanying drawing, in which:—

Fig. 1 shows the beer dispensing apparatus in front elevation.

Fig. 2 is a vertical section on line II—II of Fig. 1.

30 Fig. 3 is a top plan view of Fig. 2.

Fig. 4 shows the whole plant in side elevation.

Fig. 5 shows a vertical section showing the operating gear taken at right angles to the axes of the gear shafts.

35 A relatively large air pump 2 is mounted in one of the corners of the frame 1 which preferably consists of a cast iron casting of U-shaped cross section. A vertical cylinder 3 is mounted in the frame opposite the air pump. In the lower part 40 of frame 1 a dispensing faucet 4 and a toothed wheel gearing are arranged, the latter adapted to be actuated by a crank handle 5 on the side of frame 1. A packing 8 of rubber or the like is inserted in a metal mounting 7 on the under- 45 side of the bottom plate 6 of frame 1. A short pipe length 9 projecting from the top side of the mounting 7 extends through the bottom plate 6 and is connected at its upper end to the dispensing faucet 4, the outflow passage of which does 50 not, however, terminate in the air return pipe 10 but is formed by a pipe 11 extending through this air return pipe 10, the mouth of this pipe 11 being flush with the lower end of the short pipe length 9 and slightly below the packing surface 55 of rubber plate 8. A pipe 12 extends from the in-

flow passage of the dispensing faucet 4 and leads to the beer barrel 13 situated at a lower level (Fig. 4) than the apparatus. The beer barrel 13 is tapped in known manner by means of a pipe or tap 14 connected with the beer pipe 12 and with an air pipe 15. The air pipe 15 is connected at its upper end on a discharge aperture in the cylinder 3, in which aperture an air filter is mounted. The filter cylinder 3 is connected at its lower end with a pipe 16 which leads to a pipe 18 through a rubber lipped valve 17 of known construction. The pipe 18 is connected at one end with the cylinder of the air pump 2 and at the other end with the air return pipe 10. A rubber lipped valve 19 acting as suction valve 15 is fitted in the pipe 18 between pipe 10 and mouth of pipe 16. The air pump 2 has a reciprocable piston 20 carrying a rack 21 meshing with a pinion 22 keyed on a shaft 23 which is journaled in an extension 24 of the pump 2 and carries a 20 sprocket wheel 25 at its end projecting from frame 1. A chain 26 connects the sprocket wheel 25 with a second sprocket wheel 27 keyed on one 25 end of a gear shaft 28. This gear shaft 28 is journaled in frame 1 and connected with the handle 5 by means of gear wheels 29 and 30. A toothed segment 31 loosely mounted on shaft 28 can be coupled with this shaft by a claw clutch 33 30 adapted to be actuated by a hand lever 32. The segment 31 cooperates with a toothed wheel 34 35 keyed on the plug axle 35 of the dispensing faucet 4. The frame 1 is preferably covered by a sheet metal cap not shown in the drawing and having an inspection window for the controlling instrument which consists of a pressure gauge 36 connected with the beer pipe 12 and continually 40 indicating the pressure which exists in the barrel. The above described apparatus is fitted on the ice box or by means of a column on the dispensing counter. However, it can also be fitted 45 on an independent wall 37 behind which is the barrel 13, as shown in Fig. 4. A bracket 38 is mounted on wall 37 below the apparatus. The beer pipe 12 has a shut off cock 39 above the tap 14.

The apparatus operates in the following manner:—

The glass 40 to be filled with beer is pressed gently by hand against the packing plate 8, whereupon the crank handle 5 is turned in the 50 direction of the arrow 41. The toothed wheel gearing operates with a low transmission ratio so that no great force is required to turn the crank handle 5. The toothed wheel 29 is rotated by the toothed wheel 30 and rotates the shaft 28 with the 55

segment 31 and sprocket wheel 27. This movement is transmitted by the chain 26 to the sprocket wheel 25 and the pinion 22 which raises the rack 21 with the pump piston 20, so that the 5 air in the beer glass is sucked into the pump cylinder through the air return pipe 10, valve 19 and pipe 18. Owing to the vacuum thus produced in the glass, this glass is pressed tightly against the packing plate 8 by the atmospheric pressure and 10 hermetically sealed.

During the continued rotation of the crank handle 5 the toothed segment 31 comes into mesh with the toothed wheel 34, whereby the dispensing faucet 4 is opened. The beer then flows out 15 of the barrel with high pressure flow speed into the evacuated beer glass and the excess carbon dioxide which has been forced into the glass with the beer flows off into the pump cylinder. As soon as the beer glass is full, it easily detaches 20 from the packing plate 8. The crank handle 5 is then turned back quickly, thereby closing the dispensing faucet 4 and moving the pump piston 20 in downward direction. During this movement the air and excess carbon dioxide drawn 25 into the pump cylinder out of the beer glass is forced through the pipe 18, pressure valve 17 and pipe 16 into the air filter cylinder 3. The air filter retains all substances in suspension and any chemical impurities in the air drawn out of the 30 beer glass. The filter also lets pass all excess carbon dioxide which has flown with the beer into the glass and then into the pump cylinder, this carbon dioxide then flowing back into the barrel with the filtered air through the pipe 15.

35 The thickness of the froth layer on the beer can

be regulated by turning the crank handle 5 more or less quickly during the dispensing.

It is possible by disengaging the clutch 33 to cut off the dispensing faucet 4 from the driving gear so that only the air pump 2 is operated. This is 5 desirable, for example, when the pressure in the barrel drops and must be returned to the normal.

I claim:

1. Apparatus for dispensing beer from a barrel, comprising in combination, a tap adapted to be 10 attached to said barrel, a beer conduit extending from said tap, a dispensing faucet connected to the upper end of said conduit, an operating element for said dispensing faucet, an air suction pump having a reciprocating piston actuated by 15 said operating element, an air return conduit between said pump and said tap, an air filter in said return conduit, a transmission gear, means for connecting said transmission gear with said operating element, said transmission gear being 20 constructed and arranged to open said faucet after the pump piston has performed a suction stroke and to close said faucet when a pressure stroke is imparted to the piston, and means arranged to direct air forced from said pump 25 through said filter into said return conduit.

2. A beer dispensing apparatus as specified in claim 1, the dispensing faucet having a plug axle and the gearing having a member cooperating with said axle, a clutch adapted to disconnect 30 said member from said axle to allow the operation of the air pump whilst the faucet remains closed for re-establishing normal pressure in the barrel.
